CATHODE BEAM TRANSMITTER TUBE

Filed April 19, 1945

UNITED STATES PATENT OFFICE

2,460,093

CATHODE BEAM TRANSMITTER TUBE

Harold B. Law, Princeton, N. J., assignor to Radio Corporation of America, a corporation of Delaware

Application April 19, 1945, Serial No. 589,241

4 Claims. (Cl. 250—164)

1

This invention relates to television pick-up tubes having two-sided targets in which one side of the target is scanned by a cathode beam to discharge an electrostatic image on the other side set up by light or electrons passing through a collecting screen adjacent thereto. In one type of this kind of tube, the two-sided target has heretofore comprised a sheet of glass or other material having such thinness and conductivity as to permit the discharge within a frame time of the electrostatic image by passage of the beam electrons transversely through the thin sheet, but having sufficient resistivity to prevent substantial spreading of the image charges or electrons longitudinally of the sheet.

In pick-up tubes of the type referred to, it has been thought necessary to place the screen very close to the sheet of glass to obtain the necessary capacitance to provide a usable signal. Satisfactory signals have thus been obtained with spacings between target and screen in the neighborhood of 2 mils. In this position the screen cast a shadow or formed an image on the target that was visible in the transmitted picture. It is an object of this invention to prevent the formation of the image of the screen on targets of this type.

Another object of the invention is to increase the spacing between screen and target sufficiently to defocus the screen without substantial decrease of the maximum output signal from the screen and target.

Another object is to increase the range of high light scene brightness for cathode beam pick-up tubes with finite gamma throughout the range.

Another object is to increase the scene brightness for cathode beam pick-up tubes without reducing the gamma to zero.

Another object of the invention is to provide a cathode beam tube giving improved half-tone discrimination, especially under high lights.

Other objects will appear in the following description, reference being had to the drawing, in which:

Figure 1 is a sectional elevation of a tube having a target and screen associated in accordance with my invention.

Figure 2 is a section of the film and screen in the supporting frame.

Figure 3 is a greatly enlarged representation of a screen-target area for explaining the operation of the tube.

Figure 4 is a diagrammatic representation of the film and screen for explaining the theory of the operation.

2

Figure 5 contains two curves showing the signal current characteristics for close and wide spacing of the screen and target.

In prior art tubes referred to, the screen for collecting the secondary electrons emitted by the target, comprising a semi-conducting glass film of about two ten-thousandths of an inch in thickness, was spaced from the target surface less than the diameter of a picture element. The capacitance C between two plates (glass film and collector screen in this instance) was thought to be derivable from the usual formula

$$\frac{kA}{D}$$

in which k is a constant, A the area of one plate and D the distance between the plates. The signal obtainable from the target-screen with a scanning beam of low velocity electrons was therefore considered to be

$$\frac{CV}{t}$$

25 in which V is the potential swing of the target and t is the time the beam takes to discharge the target, or the frame time. Therefore, the extremely close spacing of 2 mils was thought necessary to provide sufficient capacity between the screen and film for a satisfactory signal.

30 In these prior art tubes, it was at first thought advisable to place the screen in contact with the glass film to obtain the desired capacitance. This, however, did not prove to be entirely satisfactory, as the target had too high a capacitance 35 to be discharged properly by the beam in a frame time. The screen was then spaced from the film about two mils, or thousandths of an inch, and it was found that sufficient capacitance remained to provide the required signal and that the target could be discharged by the beam in the frame 40 time. With this spacing, the image of the signal screen could be seen in the transmitted picture, because it was close enough to the target to be in focus, as already referred to.

45 It was determined that at least 60 and preferably 80 or more mils spacing would be required to place the screen in good unfocused position. Since the capacity was thought to vary inversely with the spacing, this abnormal spacing was considered sufficient to render the signal wholly unsatisfactory and the image of the screen in the transmitted picture was tolerated as being unavoidable. To determine how much the screen 50 image could be reduced without ruining the signal, I tested a tube with wide spacing between

the screen and target with high light. To my surprise, the maximum signal was found to be substantially the same as when the spacing between film and screen was only two mils.

In an effort to clear up the mystery of this behavior, I made tests to determine how the capacitance and the signal varied with spacing from 2 mils up to 450 mils. In making these tests, light was thrown onto the photocathode as a brief flash of duration much less than a frame time, but of sufficient intensity to charge up the target by impinging photoelectrons and secondary emission to a uniform potential of about 2 volts positive. In these tests the potential was uniform over the target because the light was projected directly onto the photocathode and not through a picture. As the beam scanned the target, it would thus pass over a few elemental areas with the exciting light on and over the rest of the areas with it off. Surprisingly, it was found that the signal was practically the same for all spacings while the beam was passing over the areas under excitation (light on). For the remaining equally charged but unexcited areas (light off), the signal varied inversely with the spacing. Only the elemental areas of the target scanned when the exciting light was off gave the reduced signal one would expect from the capacity calculated by the formula

$$C = \frac{kA}{D}$$

It therefore appeared that some hitherto unknown phenomena accounted for additional storage of picture potentials on a target in the neighborhood of the beam. The reason for this is not yet completely understood, but it is believed that in the neighborhood of the beam the capacitance of a picture element under excitation cannot be correctly calculated by the formula

$$C$$

$$N$$

where C is the capacitance of the target and N is the number of elements. It appears that the capacitance of such element is greater than this and will approach that of a disc in free space, expressed by the well-known formula

$$C = \frac{d}{\pi}$$

where d is the diameter of the element. The capacitance, calculated in this manner, can account for the high signal in my improvement.

The parallel plate capacitance of an element of the target surface approximates the capacitance of a disc in free space. A simple argument for this relation may be derived from the capacitance expression for two concentric spheres, the inner sphere being comparable to the picture element disc and the outer sphere to the collector screen behind the target. As known, the capacitance C for concentric spheres is obtainable from the equation

$$C = k \frac{r_1 r_2}{r_2 - r_1}$$

where r_1 is the radius of the inner sphere, r_2 that of the outer sphere and k is a constant. If r_1 is nearly the same as r_2 , the arrangement is similar to that of a closely spaced target and the formula becomes

$$k \frac{r^2}{r_2 - r_1}$$

where r has a mean value between r_2 and r_1 . It will be seen that this expression is, in form, like that used for determining the capacitance of a parallel plate condenser, that is,

$$\frac{kA}{D}$$

If, on the other hand, r_2 is much larger than r_1 , the expression

$$k \frac{r_1 r_2}{r_2 - r_1}$$

becomes approximately

$$k \frac{r_1 r_2}{r_2}$$

or $k r_1$. This arrangement is similar to that of a widely spaced target and screen and therefore $k r_1$ may be regarded as expressing the approximate capacity between the screen and an elemental target area under beam action. This expression is, in form, like that for the capacitance of a disc in free space, namely,

$$\frac{d}{\pi}$$

The capacitance thus is substantially independent of the spacing and is proportional to the diameter rather than to the area of the mosaic element. This would seem to explain why with high lights I am able to defocus the screen by moving it away from the target any distance without substantial decrease of the signal.

The phenomena can also be demonstrated by means of Fig. 4, where the parallel capacitances of elemental areas a to g of a small part of the target 4 are indicated by C_1 to C_7 with capacitances therebetween represented by c_1 to c_6 .

The capacitance between elemental area a and the screen 3 does not result solely from its area and the perpendicular distance between it and the screen. It results from all paths between a and the screen 3 . This contemplates a path through the intervening capacitance c_1 to area b and thence through capacitance C_2 to the screen. Another through intervening capacitances c_1 and c_2 through C_3 to the screen, and so on. The summation of all the parallel and series capacitances constitutes the total capacitance of an elemental area. Thus, the capacitance approaches the capacitance of a disc in free space.

The target in my improvement comprises a very thin imperforate film or sheet 4 of homogeneous electrically semi-conducting material, such as glass. Associated with the target sheet on the side toward the photocathode 2 is arranged the collecting screen 3 . The semi-conducting film

may have a specific resistance lying within the range of 10^9 to 10^{12} ohm-centimeters, as this has been found satisfactory. It has been found that a thin sheet of glass, known in the art as Corning G-8 glass, has the desired specific resistance of approximately 5×10^{10} ohm-centimeters

when formed in very thin films, such as two ten-thousandths of an inch in thickness, but other glasses of suitable resistivity may be used. The thin glass film may be constructed and stretched out across ring 4 , for example, by the method disclosed in the application of Albert Rose, filed September 20, 1940, Serial No. 357,543, for which application Serial No. 631,441 was filed November 28, 1945, as a continuation, after which application Serial No. 357,543 was abandoned, but known.

edge of these details is not necessary for an understanding of my invention and the description need not be repeated here.

The wire mesh screen 3 is assembled in spaced non-focused position from the film 1 in ring 4, such as by the metal rings 5 and 6 (Fig. 2). The spacing between the screen and film should preferably be more than 60 to 80 mils to defocus the screen properly.

In the use of my invention I prefer to employ the tube having a multiplier construction, for example, like that shown in the application of Paul K. Weimer, filed September 16, 1944, Serial No. 554,494 now United States Patent 2,433,941, issued January 6, 1948, to which reference is made for various details of construction not required for an understanding of my invention. With this tube, the operation of my widely spaced target-screen unit may be explained as follows:

Assume that the left-hand surface of the target sheet 1 in Figs. 1 and 3 is scanned by the electron beam 7 (greatly enlarged in Fig. 3) and that photoelectrons, as at 8, are projected from the photocathode 2 by light rays L from an object focused thereon. These photoelectrons are focused through screen 3 by coil 9 on the right-hand surface of the sheet 1, such as over the elemental area B, and accelerated by the electrostatic field of anode 9' at such velocity as to charge it positively by the secondaries emitted therefrom. The secondaries are collected by screen 3, which is, as usual, maintained at or slightly above the voltage of the gun cathode 10. The coil 9 maintains a magnetic focusing field for the beam electrons, as well as the photoelectrons. Since the area B is made positive by the photoelectrons, the space around B, including an area of the screen 3, will also be positive by electrostatic influence. Points very near B, such as the area A, will have almost the same potential as B. A portion of the electrons of the scanning beam 7, in passing over the area A, will land and deposit enough charge to reduce the potential on the area A to the potential of the gun cathode and the remainder 11 (Fig. 1) will return toward the cathode. The positive charge at B and the negative charge at A on target 1 unite by conduction through the thin sheet of semi-conducting material and both areas A and B return to their original uncharged state in a frame time, thus producing a signal by modulation of the returning beam 11, the electrons of which land on the first stage 12 of the multipliers around the gun, as shown and described in detail in said Weimer application, but it may be briefly said that the secondaries bombard other secondaries from the surfaces 13 through shield screens 14 successively from the first stage 12 to the second stage 15, third stage 16, fourth stage 17 and the final disc stage 18. The secondaries bombarded from this final stage are collected by signal electrode 19 of negligible capacitance with the target. The signal then passes at 20 to suitable amplifiers and other utilization devices, not shown.

In Fig. 5, signal vs. light curves A and B are for closely and widely spaced screens, respectively. The ordinates are the signal output values in microamperes at the target. The abscissas are the signal input in microamperes or total photocathode current, the illumination on the photocathode (10 microamperes/lumens sensitivity) in foot candles and the high light scene brightness in candles/ft.², using a lens of f/2.3. At very low illumination and photocathode current the two curves are the same, but at 21 the curves sep-

arate. At this point the parallel plate capacitance

kA

D

- 5 has been saturated and further increases in signal in curve B are due to the disc or elemental area capacitance kd alone, as hereinbefore described. The signal continues to increase with finite gamma up to 22, at which point gamma becomes zero, gamma being the exponent in the equation $S=kL\gamma$, where S is the signal output at the target and L is the light on the photocathode. With close spacing (curve A), the gamma is finite only up to 23 and is zero therebeyond. Thus, 10 by increasing the spacing between the target and screen, I remove the screen from focusing position and also have finite gamma at high light, or scene brightness, where it would be zero with the closely spaced target and screen (curve A). 15 In curve A the signal output saturation occurs at 10^{-1} foot candles of illumination on the photocathode, but in the widely spaced screen and target (curve B) signal output saturation does not occur until 10 foot candle illumination is reached. 20 25 This gives greater half tone discrimination at high lights.

In accordance with my invention, moving the screen from the previously employed close distance of 2 mils to beyond a distance of 60 to 80 mils, enables me to entirely eliminate the image of the screen 3 in the picture without any appreciable reduction of signal strength and with finite gamma at high light. I have advanced a theory explaining this seeming paradox, but the invention is not limited to this or any other theory or explanation.

Having described my invention, what I claim is:

1. A television transmitting tube comprising 40 means for producing a uniform magnetic focusing field, an envelope containing a cathode beam gun, a glass film target in said field, a collecting screen spaced more than approximately 60 mils from the target on the side remote from the gun and means for forming an electrical picture image on said target through said screen.

2. A television transmitting tube comprising 50 means for producing a uniform magnetic focusing field, an envelope containing a cathode beam gun, a glass film target in said field, a collecting screen spaced more than approximately 60 mils from the target on the side remote from the gun, means for forming an electrical picture image on said target through said screen and a signal electrode of negligible capacitance with said target.

3. A television transmitting tube comprising 60 means for producing a uniform magnetic focusing field, an envelope containing a cathode beam gun, a glass film target, a collecting screen spaced more than approximately 60 mils from the target on the side remote from the gun, means for forming a desired electrical picture image on said target through said screen, means for scanning the beam of said gun over said target to discharge said electrical picture image and a signal electrode of negligible capacitance with said target for collecting the electrons of said beam 70 after discharge of said image.

4. A television transmitting tube comprising an evacuated envelope containing a cathode ray beam gun, a photocathode, a target consisting of a thin sheet of semiconducting material, field 75 producing means for focusing electrons from said

gun on one surface of said target and electrons from said photocathode on the other surface thereof, said target being positioned in a focal plane of said electrons, a screen positioned outside said focal plane between the photocathode and the target and a signal electrode spaced widely from said target having negligible capacitance therewith.
